P. A. MYERS.
PRESSURE CONTROLLING DEVICE.
APPLICATION FILED JUNE 5, 1916.

1,217,338.

Patented Feb. 27, 1917.

UNITED STATES PATENT OFFICE.

PHILIP A. MYERS, OF ASHLAND, OHIO, ASSIGNOR TO F. E. MYERS AND BROTHER, A COPARTNERSHIP CONSISTING OF FRANCIS E. MYERS AND PHILIP A. MYERS, OF ASHLAND, OHIO.

PRESSURE-CONTROLLING DEVICE.

1,217,333.

Specification of Letters Patent. Patented Feb. 27, 1917.

Original application filed September 18, 1915, Serial No. 51,298. Divided and this application filed June 5, 1916. Serial No. 101,812.

To all whom it may concern:

Be it known that I, PHILIP A. MYERS, a citizen of the United States, residing at Ashland, in the county of Ashland and State of Ohio, have invented certain new and useful Improvements in Pressure-Controlling Devices, of which the following is a specification, reference being had therein to the accompanying drawing.

10 This invention relates to a pressure controlling device which is applicable to various mechanisms but is more particularly designed for use with spray pumps, or the like, in which it is desired to interrupt the operation of the pumping instrumentalities when the resistance to the movement of the piston has become abnormal, without interrupting the application of power to the operating devices. Pumps of this kind have 15 been heretofore designed but for the most part they have not been of a satisfactory construction or operation. The present application constitutes a division of the application filed by me Sept. 18th, 1915, Ser. No. 25 51,298, which has been issued as Patent No. 1,191,453, dated July 18th, 1916.

The object of the present invention is to provide a pump of this type in which the controlling mechanism will be of a very simple and of a highly practical character, thus not only cheapening the construction of the pump but also rendering it more certain in its operation and less liable to get out of order or to fail to operate. To this end, it 35 is a further object of the invention to provide improved means for applying the controlling spring to the operating mechanism, and to so arrange the mechanism that a short spring supported solely by the connecting 40 rod may be utilized to yieldably control the action of the connecting rod.

In the accompanying drawing, the figure is a side elevation, partly in section, of one embodiment of the invention.

45 In the embodiment here shown the pump comprises a base 1 upon which is mounted a cylinder or cylinders 2. Mounted in each cylinder is a piston 3 which serves to draw the fluid in through the inlet pipe 4 and to 50 force the same out through an air chamber 5 and discharge pipe 6. This discharge pipe is usually connected with a tank in which the fluid is stored under air pressure and to which are connected the hose and nozzle, or

other distributing devices. This tank is constructed to withstand a certain predetermined pressure and to avoid injury to the tank and possible injury to the operator it is essential that the pressure should not rise materially above the predetermined amount. 60 Relief valves are commonly used to control this pressure but their operation is unsatisfactory, principally because of the corrosion due to the character of the spraying fluids.

The operating mechanism for the pump 65 may be of various kinds, but preferably comprises a crank shaft 7 journaled in uprights 8 carried by the base 1, and driven by means of gearing 9 and 10 from a shaft 11 to which power may be applied either by a belt or in any other suitable manner. To control the movement of the movable part of the mechanism I have interposed between the same and another part of the apparatus a two part connecting rod or toggle, the two parts of 75 which are held normally against relative movement by a spring. In the present embodiment of the invention the toggle serves to transmit power from the shaft to the piston and to this end a toggle is interposed 80 between the crank shaft and each piston. The two members of each toggle or connecting rod, as shown at 12 and 13, are pivotally connected one to the other, at 14, and, at those ends remote from the axis of said connection, are pivotally connected respectively to the crank shaft and to the piston 3, as shown at 15 and 16. The movement of the two members of the connecting rod about their intermediate axis 14, by which they are 85 connected one to the other, are so controlled that this axis cannot move into alignment with the axes, 15 and 16, of the connections between the ends of the rod and the piston and crank shaft, respectively. The movement of this intermediate axis toward a line 90 extending through the axes 15 and 16 of the rod is limited by co-operating parts of the two members of the rod. As here shown, one member, 13, has a projection or lug 17 100 extending beyond the axis 14 and arranged to engage a part or lug 18 carried by the other member, 12, of the rod when the two parts of the rod are moved toward alignment, the arrangement of the parts 17 and 18 being such that the axis 14 cannot be moved into line with the axes 15 and 16. Preferably, one of the parts, as here shown

the part 18, is provided with a cushion, such as a block of leather, to deaden the sound and to absorb the shock due to the contact of these parts.

5 Each member of the connecting rod is provided with an arm 19 extending outwardly some distance therefrom and an expansion spring 20 secured at its ends to the respective arms through the instrumentality of the 10 adjusting pivoted portions 21 which are pivoted to the ends of the arms 19 at 22. It will be obvious that as the two members of the rod are moved about the axis 14 the ends of the arms 19 will be moved away from or 15 toward each other, in the one instance, the movement being accomplished against the tension of the spring, and in the other instance being caused by the contraction of the spring. In other words the spring 20 20 tends to resist the movement of the intermediate axis away from the line extending through the axes 15 and 16, the strength of this spring being such that it will prevent any movement of either member of the rod 25 about the axis 14 so long as the resistance to the movement of the piston does not become abnormal, that is, the pressure in the tank does not exceed a predetermined amount.

The operation of the device will be readily 30 understood from the foregoing description and it will be apparent that I have provided a controlling mechanism which is very simple in its construction, which is certain in its operation and which is of a very strong, 35 durable character. Further, it will be apparent that the device is readily adjustable to cause the same to yield at different pressures; and further, that the device comprises very few parts; and that the character and 40 arrangement of these parts are such that they will not readily get out of order or lock or bind in such a manner as to interfere with or prevent the operation of the mechanism in the prescribed manner.

45 While the invention was primarily designed for, and has been illustrated as applied to, a spray pump, it will be apparent that it can be applied to pumps of other kinds or to mechanism other than pumps 50 where the operation is similar and the device would be useful, and further, it will be understood that the construction shown and described has been chosen for the purpose of illustration only and that I do not wish to be limited thereto, as obvious modifications will occur to a person skilled in the art.

Having thus fully described my invention, what I claim as new and desire to secure by Letters Patent, is:

55 1. In a pump, the combination, with a piston and a crank shaft, of a two part connecting rod interposed between said piston and said shaft, the two part rod having its ends pivotally connected respectively with 60 said shaft and said piston and having its

two members pivotally connected one with the other, and a spring secured at its ends to the parts of said rod and adapted to travel with said rod and to act thereon to hold the two members thereof against relative movement during the normal operation of said pump and to permit said members to have relative movement when abnormal resistance is offered to the movement of said piston.

2. In a pump, the combination, with a piston and a crank shaft, of a two part connecting rod interposed between said piston and said shaft, the two part rod having its ends pivotally connected respectively with said shaft and said piston and having its two members pivotally connected one with the other on an axis arranged between but out of alinement with the axes of the first-mentioned connections, and an expansion spring secured to both members of said connecting rod and acting thereon to hold said members against relative movement during the normal operation of said pump and to permit said members to have relative movement when abnormal resistance is offered to the movement of said piston.

3. In a pump, the combination, with a piston and a crank shaft, of a two part connecting rod interposed between said piston and said shaft, the two part rod having its ends pivotally connected respectively with said shaft and said piston and having its two members pivotally connected one with the other on an axis arranged between but out of alinement with the axes of the first-mentioned connections, one member of said rod having a part extending beyond said intermediate axis and arranged to engage a part carried by the other member of said rod to limit the movement of said intermediate axis toward a line extending through the two first-mentioned axes, and a spring secured at each end to the two members of said rod and tending to move said intermediate axis toward said line.

4. In a pump, the combination, with a piston and a crank shaft, of a two part connecting rod interposed between said piston and said shaft, the two part rod having its ends connected respectively with said shaft and said piston and having its two members connected one with the other on an axis arranged between but out of alinement with the axis of the first-mentioned connections, the two members of said rod having parts adapted for connection with the respective ends of a spring and arranged to be moved toward or away from each other when said members are moved about said intermediate axis, and an expansion spring connected to said parts of said members.

5. In a device of the character described, the combination, with a driving member and a driven member, of a two part connecting rod having its two parts pivotally connected

- one to the other and its ends pivotally connected respectively with said driving member and said driven member, means to hold the axis on which the two parts of said rod 5 are connected one to the other out of alinement with the axes of the ends of said rod, and a spring having its ends secured to the two parts of said rod and tending to resist the movement of the two parts of said rod 10 about the axis on which they are connected one to the other.
6. In a device of the character described, the combination, with a driving member and a driven member, of a two part connecting rod having its parts pivotally connected one to the other and its ends pivotally connected respectively with said driving member and said driven member, means to hold the axis on which two parts of said rod are connect- 15 ed one to the other out of alinement with the axes of the ends of said rod, arms projecting from said rods, and an expansion spring connecting the ends of the arms and tending to keep the members of said rod in normally 20 extended and rigid position.
7. In a pump, the combination, with a piston, and a crank shaft, of a two part connecting rod interposed between said piston and said crank shaft, means carried by said 25 rod for holding the two parts of the same normally in their extended position and for permitting the relative movement of the two parts of said rod when abnormal resistance is offered to the movement of said piston, 30 said means comprising a pair of projecting arms mounted on the rod, and a spring se- 35 cured at its ends to the ends of said arms.
8. In a mechanism of the character de- 40 scribed, a movable member, a controlling de- 45 vice for said movable member comprising a toggle having one end pivotally connected with said movable member and having its other end pivotally connected with another part of said mechanism, the members of said toggle having parts coöperating to prevent the intermediate axis of said toggle from being moved into alinement with the axes at the ends of said toggle, the respective members of said toggle being provided with arms, and a spring having its ends attached 50 to the ends of the arms and acting to hold the parts of said toggle normally in engage- 55 ment.
9. In a mechanism of the character de- 60 scribed, a movable member, a controlling de- 65 vice for said movable member comprising a toggle having one end pivotally connected with said movable member and having its other end pivotally connected with another part of said mechanism, one member of said toggle having a stop near the intermediate axis of the same and the other member of said toggle having a part projecting beyond said intermediate axis and arranged to en- 70 gage the stop and prevent said intermediate axis from being moved into alinement with the axes at the ends of said toggle, and an expansion spring secured at its ends to the respective members of the toggle and acting to hold said projection and said stop nor- 75 mally in engagement.

In testimony whereof, I affix my signature.

PHILIP A. MYERS.
